CLAIM

The ornamental design for a part of container, as shown and described.

DESCRIPTION

FIG. 1 is a perspective view from above and one side of the container showing the new design;

FIG. 2 is a side view thereof;

FIG. 3 is a side view thereof, rotated clockwise 90° from FIG. 2;

FIG. 4 is a side view thereof, rotated clockwise 90° from FIG. 3;

FIG. 5 is a side view thereof, rotated clockwise 90° from FIG. 4;

FIG. 6 is a top plan view thereof;

FIG. 7 is a bottom plan view thereof; and,

FIG. 8 is a perspective view from below and one side.

The broken lines shown in the Figures are for illustrative purposes only and form no part of the claimed design.
